INVENTOR

Malcolm Hard

BY

O. V. Thiele

ATTORNEY

In said former application a form of connecting piece is disclosed in which the return pipe 8 extends through the center of the connecting piece. My invention can likewise be applied to this form, and Figs. 6 and 7 illustrate this. The inlet 3a delivers steam and any entrained moisture tangentially to the connecting piece 5a and the partition 9a functions just as the partition in the form first described.

10 Other variations will also be possible without sacrificing the underlying inventive thought.

What I claim is:

1. In a superheater element for use in a locomotive flue to absorb heat from the gases flowing through the flue and comprising a plurality of tubes arranged to receive steam from a common inlet pipe, a connecting piece into which the inlet pipe opens and from which the tubes extend, the inlet pipe opening into the connecting piece tangentially, and the tubes being connected to the connecting piece at points adjacent to its outer wall.

2. In a superheater element for use in a locomotive flue to abstract heat from the gases flowing through the flue and comprising a plurality of tubes arranged to receive steam from a com-

mon inlet pipe, a connecting piece with a cylindrical interior, the inlet pipe opening tangentially into the interior and the tubes being connected to the connecting piece along the cylindrical wall equidistantly from the axis of the cylinder.

3. In a superheater element for use in a locomotive flue to abstract heat from the gases flowing through the flue and comprising a plurality of tubes arranged to receive steam from a common inlet pipe, a connecting piece with a cylindrical interior, the inlet pipe opening tangentially into the interior, the tubes being connected to the connecting piece along the cylindrical wall, and a partition between the opening of the inlet pipe and the tube connection points, the partition having a central aperture.

4. A connecting piece in accordance with claim 3, the partition being at right angles to the axis of the connecting piece.

5. A connecting piece in accordance with claim 3, the partition being at right angles to the axis of the connecting piece and the inlet pipe opening into the connecting piece obliquely to its axis.

25 MALCOLM HARD.
